(57) **CLAIM**

The ornamental design for a wheel chock hose and cable guide, as shown and described.

DESCRIPTION

FIG. 1 is an isometric view, taken generally from the front, top, and right side, of a wheel chock hose and cable guide showing my new design;

FIG. 2 is an isometric view thereof, taken generally from the rear, top, and right side;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

In the drawings, the broken lines show portions of the article that form no part of the claim.

1 Claim, 5 Drawing Sheets
